UNITED STATES PATENT OFFICE

2,102,190

DISCHARGE APPARATUS AND METHOD

Robert E. Barclay, Chicago, Ill., assignor to Federal Electric Company, Inc., Chicago, Ill., a corporation of New York

Application January 5, 1934, Serial No. 705,393
Renewed August 10, 1937

12 Claims. (Cl. 176—124)

My invention relates in general to electronics and has more particular reference to electrical discharge apparatus, the invention more specifically relating to gaseous conduction apparatus 5 and the method of operating the same from a low voltage source of electrical power.

An important object is to provide a gaseous conduction device of the class described which can be started at low applied voltage.

10 Another object is to provide means to excite a gaseous conduction lamp of the character described so that it can be started in operation at low voltage.

Another object is to provide a lamp combination 15 wherein an exciter, comprising a conductor, is arranged in position to induce high frequency electrostatic effects in the lamp in order to improve its starting and operating efficiency.

Another object is to operate a discharge lamp 20 of the character mentioned as a rectifier and to encircle the discharge path with an exciter comprising a conductor disposed about said lamp and adapted to excite the gaseous conduction medium of the lamp to permit the same to be 25 started in operation at relatively low applied voltage.

Another important object is to provide a device 30 of the character mentioned, which is operable from a relatively low voltage alternating current power source, a further object being to form the lamp in a manner permitting detachable mounting in a power outlet socket or lamp fixture, so that the same can be used as a replaceable unit in the same manner as an ordinary incandescent lamp.

Another important object is to utilize a high voltage discharge device consuming a relatively small amount of power, in conjunction with a discharge device consuming relatively more power 40 and normally requiring a relatively high voltage for its operation, in order to permit the latter device to be operated at relatively low voltage and thus reduce the total power required to operate the combination.

45 Another object of the invention is to provide a hot cathode discharge lamp unit having all of the electrodes disposed in one end of the lamp in a manner facilitating connection of the lamp with external power delivery circuits.

50 Another object is to provide a discharge lamp having a cathode target which can be started in operation without preliminary heating.

Another object is to provide a lamp of the 55 class mentioned having an envelope defining a pair of discharge channel portions separated by dielectric means, with anode and cathode electrodes at the ends of said portions; a further object being to dispose the anodes and cathode

60 in the ends of the legs to facilitate connecting the

device in suitable actuating circuits at one end of the envelope.

Among the important objects of the present invention is to provide a device of the character described having novel structural features, whereby the device is neat and compact, being thus particularly adapted for use as a readily replaceable lamp unit.

Numerous other objects and advantages will be apparent from the following description, 10 which, taken in connection with the accompanying drawings, discloses preferred embodiments of the invention.

Referring to the drawings:

Figure 1 is a perspective view of a cathode target lamp embodying certain features of my present invention;

Figures 2 and 3 are sectional views taken respectively substantially along the lines 2—2 in Figures 1 and 3, and along the line 3—3 in Figures 1 and 2;

Figure 4 is a sectional view taken longitudinally through the lamp shown in Figure 1, illustrating a modified mode of applying the electrodes and cathode target, and also showing an activating 25 element comprising means forming a circuit encircling the lamp in order to improve the operating efficiency thereof, the power delivery circuits for full wave rectified current operation of the lamp and the power circuit for operating the 30 activating element being shown diagrammatically;

Figure 5 is a diagrammatic view of the lamp showing a modified power delivery circuit;

Figure 6 is a diagrammatic view of the lamp 35 showing modified cathode means comprising spaced electrodes;

Figure 7 is a diagrammatic view of a lamp embodying the present invention as arranged for full wave, three-phase operation;

Figure 8 is a diagrammatic view of a modified form of the lamp shown in Figure 7;

Figure 9 is a diagrammatic view of a lamp embodying my present invention arranged for half-wave operation and showing a filamentary cathode target;

Figure 10 is a diagrammatic view illustrating a lamp similar to that shown in Figure 9 with cathode means comprising spaced electrodes;

Figures 11 and 12 are sectional views showing 50 a commercial form of the lamp shown in Figure 10, with which is associated an activating element similar to that shown in Figure 4; Figure 11 being taken substantially along the line 11—11 in Figure 12; and Figure 12 being taken substantially along the line 12—12 in Figure 11; and

Figure 13 is a schematic view illustrating a modified form of lamp embodying my present invention.

To illustrate my invention, I have shown on 60

the drawings, an electronic discharge device 11, comprising a sealed envelope 13, formed preferably of any suitable light-transmitting material, such as glass and forming a channel 17 containing a suitable gas and having spaced electrodes 23 and 25 associated with the channel. The electrode means are preferably mounted in housings 40 comprising envelope extensions formed or otherwise connected on the envelope 10 and in communication with the discharge channel.

Means is provided for connecting suitable power-supplying circuits with the electrodes to apply a potential difference therebetween in order 15 to set up electrical discharges in the channel 17 and also to supply power for exciting the electrodes as by heating the same in embodiments where excited electrodes are employed.

The envelope means is preferably, though not 20 necessarily, arranged so that the channel 17 is of generally U-shaped configuration comprising a pair of sealed channel portions 18 and 22 disposed in parallel and adjacent relationship and having communication only at one end of the envelope, said channel portions being preferably 25 separated, except at their communicating ends, by dielectric means preferably in the form of an integral partition 19 extending within the walls of the envelope. The channel portions, also, may 30 be separated by the dielectric means throughout their entire length and provided each with an electrode at its opposite end; if desired, the electrodes in the ends of the channel portions, opposite from the electrodes 23 and 25, being electrically 35 connected together in any suitable fashion. I prefer, however, to directly connect the channels together at an end of the envelope to form a single closed U-shaped chamber or channel 17, as shown in Figure 4.

40 The envelope 13, may comprise a tube bent at its mid-point, but I prefer to fabricate the device from a suitable length of partitioned multi-bore tubing of the character described in United States Patent No. 1,904,348, covering the Method 45 of making multi-bore tubing, which issued to me April 18, 1933, by sealing a dome 20 on one end of the tube and by sealing the opposed ends of each arm 18 and 22, with suitable electrode means positioned therein, since such an envelope construction has certain inherent features of advantage, which will hereinafter be more fully 50 described. My present invention however, is not necessarily limited to the particular envelope construction illustrated, but may be applied in 55 devices having one or more discharge channels arranged in any desirable or suitable form or configuration, and including a tubular envelope providing a straight discharge channel with associated spaced electrodes.

60 I prefer, however, to dispose the opposite ends of the channel 15 somewhat adjacently so that the lower end of the envelope, including the electrode housings 40, may be mounted in and supported by the base 15, which is or may be 65 provided with terminal means 21 of suitable form whereby to connect the electrodes with a suitable source of electrical power, such, for instance, as a socket receptacle adapted to receive the base and the terminals 21 and connect the same 70 in external power circuits with which the socket receptacle is associated.

Discharge devices, embodying my present invention, depend for their operation upon the initiation and maintenance of electrical discharges in an ionized field between spaced sta-

tions, which are preferably in the form of spaced electrodes, carrying opposite electrical charges, the discharge occurring from a negatively charged station or anode to a positively charged station or cathode, called the target. Such dis- 5 charges may be initiated by applying alternating electrical potential between spaced electrodes, in which case the electrodes alternate their status as anode and cathode with each alternation of applied potential. The device however may also 10 be operated by applying direct current between the electrodes, in which case the anodes and cathodes maintain their character as such throughout the discharging operation. I prefer, however, to establish electrical discharge by ap- 15 plication of electrical potential of alternating character on a discharge device having permanent cathode electrode means, by providing a plurality of anode electrodes spaced apart from the cathode target and applying the alternating cur- 20 rent potential between the anode electrodes while connecting the cathode target to a neutral point in the alternating current supply system. By this expedient, the device is constituted as a rectifier, the discharges taking place in a unidirectional 25 manner successively from the several anodes to the cathode target, during each alternation of the potential applied to the anodes.

Certain phases of my present invention, how- 30 ever, may have application in devices, in which alternating current is applied at the spaced electrode stations in an ionized field to permit the discharge to take place alternately in opposite directions between the spaced points of application, but the invention relates more particu- 35 larly to devices having a permanent cathode target receiving unidirectional discharges. Moreover, the invention relates to devices in which one or more of the electrodes are artificially excited in order to promote electron emission as well 40 as to devices in which the electrodes are not excited. The invention also includes devices wherein the artificially excited electrode is of filamentary nature as well as devices wherein electrode excitation is accomplished in other ways. 45

Ordinarily, it may be necessary to apply a relatively high potential difference between the electrodes in order to initiate and maintain dis- 50 charges in the gas-filled channel 17. However, by providing means for exposing the envelope to the effects of high frequency oscillations, such, for instance, as are generated in an exciter ele- 55 ment X, I am able to initiate and maintain a discharge in the channel 17 with materially less voltage applied between the discharging elec- 60 trodes. This advantage is especially noticeable when the main element 11 is formed with closely adjacent discharge portions 18 and 22 separated by dielectric means between the channel por- 65 tions, but is also apparent when a straight dis- 70 charge channel is employed.

The exciter X, when in operation, promotes ionization of the gaseous media in the channel portions 18 and 22, and permits discharges to be initiated between the electrodes therein more 65 readily and hence at lower applied voltage than when no exciter is used. The exciter may be of any suitable or preferred form, preferably comprising a conductor or conduit which encircles the element 13 and which carries high frequency 70 impulses. As shown in Figure 4, the device X preferably comprises a discharge element or tube 45 containing a gaseous conductor, the tube being wound in helical form and mounted in position to encircle the element 13. The device 75

may comprise a sealed tube preferably of glass, the opposite ends of which are provided with electrodes 47, the tube being evacuated of air and filled with a suitable gas capable of being ionized to sustain electrical discharges and having connections provided whereby to deliver a suitable electrical potential between the electrodes 47 in order to set up discharges through the tube between the electrodes 47. The exciter may be 5 powered in any suitable fashion as by connecting the electrodes 47 to the secondary winding 49 of a transformer 51, the primary windings 53 of which are connected to any suitable power source. The opposite electrode-containing ends 10 of the element 45 also may be turned downwardly on opposite sides of the envelope 13, which the element 45 encircles. These downwardly turned ends 55, as shown in Figure 11, may be fitted into the support casing 15 in the spaces between the 15 laterally projecting housing extensions 40 containing the electrodes 23 and 25, which ends are also preferably embedded in the insulating compound contained within the housing 15. The electrodes 47 also may be electrically connected 20 with terminals 57 carried by the casing 15 whereby the element 45 may be connected in an external circuit for delivering electrical power to the element 45 when the casing is mounted in a suitable outlet socket.

25 I may also use the exciter element in conjunction with the ordinary form of discharge device comprising a tube having a single channel, either straight with electrodes at the opposed ends of the tube or bent to provide a U-shaped channel.

30 The purpose of the element X is to provide high-frequency current oscillations in the vicinity of the channel 17 and thus excite the main discharge device 11 and not only improve its operating efficiency but also permit discharges 35 to be initiated in the main element between the electrodes 23 and 25 at substantially lower applied voltage at the electrodes than is necessary where the device 11 is operated without the influence of the exciter. I also may increase the 40 exciting effect of the exciter by interposing plate means, preferably comprising metal foil 141, between the exciter and the discharge device. Since the power required to operate the element 45 is substantially large compared with that required for the exciter, it will be obvious that by 45 utilizing the exciter X, a substantially less powerful, and therefore, less expensive transformer 35 will be required to power the device 11.

50 Although I have shown the exciter as a helically wound element encircling the envelope 13 substantially throughout its entire extent, advantageous results are obtained even when the exciter device encircles the envelope 13 for only a portion of its length. The exciter, especially 55 when in the form of a tubular discharge element, does not impair the illuminating effect of the main element 11, since its coils are relatively widely spaced and by suitably selecting the gases in the device 45 and the channel 17 of the device 11, 60 I can produce any desired color combination and thus produce a lamp capable of achieving attractive decorative effects. I do not, however, herein claim the production of combined color lighting effects, since the same comprises subject matter claimed in my co-pending application Serial No. 30,305, filed July 3, 1935, for Gaseous conduction device.

65 The exciter may be employed with satisfactory results in discharge devices of various forms and I have shown the same as applied to devices

having permanent cathode target means as well as in devices wherein the cathode and anode alternate; and while the exciter operates most satisfactorily where the device has integral glass partition means disposed between the legs 18 5 and 22, it has advantages also where the envelope does not have adjacent channel portions 18 and 22.

70 I have illustrated the exciter X as applied to several modified constructions but I do not wish to limit the invention to any particular combination and it should be understood that the tubular discharge form of the exciter may be applied to all of the illustrated discharge devices as well as to the ordinary forms known to the prior art. The particular forms of discharge devices, which I have shown herein, in conjunction with the exciter to illustrate one phase of the invention, each contain individual features of novelty which I shall now describe.

75 In Figures 1-12, one end 18 of the channel 17 is provided with permanent cathode-forming means C, while the other end 22 is provided with anode means A preferably comprising one or more electrodes 25 of any suitable form and preferably similar to the electrode shown in my co-pending application, Serial Number 570,717, filed October 23, 1931, for Electrical discharge device and electrode for same, which has matured as Letters Patent of the United States No. 2,062,- 80 959, issued December 1, 1936. The cathode-forming means C may, as shown in Figures 1, 2, 3, 4, 5, 7, and 9, comprise a filament 23, adapted to be excited as by heating, or, as shown in Figures 6, 8, 10, 11, and 12, comprise a pair of spaced- 85 apart electrodes 26 of suitable form adapted to be excited by setting up a discharge therebetween. Alternatively, the cathode means, as shown in Figure 13, may comprise a single electrode.

90 In Figures 13, 14 and 15 I have shown discharge devices having modified electrodes, of a type adapted to function alternately as anodes and cathodes, as well as to operate in a manner continuously maintaining their status as anodes or cathodes as the case may be.

95 The devices, particularly those shown in Figures 4 and 13, are adapted for operation through the application of unidirectional electrical potential between its electrodes 23 and 25, with the electrode 25 functioning as anodes while the electrode 23 comprises a cathode adapted to operate as such without excitation, and the electrode 23 may be formed with grooves to increase its surface area and of an alloy hereinafter more particularly described and especially well adapted for use as a cathode material. If desired, both electrodes 23 and 25 may be made like the electrode 23, in which case either electrode may function as a permanent cathode in the event that the device is actuated by direct current applied 100 between the spaced electrodes 25, the electrode 23 in such case being eliminated. The device, however, may be operated with alternating potential applied between the electrodes if desired.

105 In Figure 14, I have shown electrodes 23 and 25, both of filamentary character so that both may be excited as by the application of current to the filament from an external source. If desired, the filaments may be enclosed in a protective casing, which is warmed by the filament and forms the actual electrode while protecting the filament from the discharges set up between the electrodes. The device illustrated in Figure 14 may be operated either with alternating or unidirectional potential applied between the elec- 110

trodes 23 and 25 and either electrode may function as the permanent cathode when direct current is used to actuate the device.

In Figure 15, I have shown electrodes 23 and 25 provided with filamentary exciter wires coiled thereabout with one end of each coil closely spaced with respect to its corresponding electrode. The opposite ends of the coils are extended through the walls of the envelope and connected together or the opposed ends of the exciter coil 145, if the same is employed. In either event, the application of a potential difference between the electrodes will cause a flow of current through the filaments which will heat the electrodes by induction as well as by conduction and radiation. Alternately, the filaments may be energized by applying electrical potential differences from any suitable source directly between the end connections of each coil outside of the envelope and the electrode connections.

In Figure 13, I have shown a discharge device, which may be used either alone or in conjunction with the exciter X. The discharge device is preferably formed as shown with its arms 25 in adjacent parallel relationship with an electrode at the end of each arm and an intermediate electrode at the junction of each arm. The device may and preferably is actuated with the intermediate electrode functioning as a cathode, while the remaining electrodes comprise anodes. The anodes may be connected to an alternating current power source, such as a transformer winding, or its equivalent, while the cathode is connected to a neutral point of the 30 transformer winding. Discharges will occur alternately from each anode to the cathode and unidirectional current will flow in the cathode connection to the winding. The device therefore functions as a rectifier and produces direct 35 current between the cathode and neutral point of the winding in response to the delivery of alternating current to the anodes. Other uses and modes of operation of the device will be apparent and the device may be arranged for 40 three-phase operation by forming the envelope with a trifoil partition providing three discharge arms in place of the two shown in the drawings and by providing an extra anode in the extra arm. In such a case, the power distributing 45 50 winding may be as shown in Figure 9, with conductor 28 eliminated, where a cold cathode is employed. The intermediate or cathode electrode may, of course, be of any form and means may be provided for exciting the same in any manner 55 including the specific cathode arrangements shown herein. The cathode means, when in the form of one or more electrodes, may, if desired, be similar to the electrodes 25. I prefer, however, to utilize for the cathode means, a special 60 electrode material comprising an alloy of barium with some other suitable metal carrier, such as aluminum, or chromium and manganese, or nickel.

I have found the following barium alloy to be suitable as a cathode particularly where the device is to be operated without artificially exciting the cathode, as is the case in the form shown in Figure 13, since the material will provide an electrode operable as a cold cathode 65 without destructive sputtering:

Percent

Aluminum	-----	90
Barium	-----	10

76 I do not, however, claim herein any barium-

containing alloy as an electrode material or the combination of a lamp having electrodes formed of any of the barium-containing alloys herein mentioned, since the same forms the subject matter of a co-pending application filed by me 5 on January 9, 1937, under Serial No. 119,857, for Electrode and devices embodying the same.

Each of the electrodes 25 has a corresponding conductor 27 and the cathode means at least one conductor 29 and, if the cathode is of a type 10 adapted to be excited, an additional exciting conductor 28, all of said conductors extending outwardly through the envelope to enable said electrodes and the cathode means to be electrically connected in external electrical circuits, 15 the points at which the conductors 27 and 29 penetrate the walls of the envelope being sealed to prevent the ingress or egress of gases. Preferably each electrode 23 and 25 is arranged in an individual electrode housing 40, which is sealed 20 onto the envelope 13 so as to expose the electrode in the channel 17, although each may be sealed directly in the channel 17 if desired. The channel 17, after having been evacuated and purified, is filled with a suitable gaseous medium, 25 such as neon, argon, crypton, mercury vapor, or other gas capable of providing an ionized path for an electronic flow or discharge between the anode and cathode means.

The evacuation and purification of the envelope and electrodes and admission of gases to the purified channel may be accomplished in any suitable or desirable manner as is known in the art.

As heretofore mentioned, the electrode-carrying ends of the envelope are preferably adjacently disposed and mounted in a supporting base 15, and, in order to facilitate the connection of the electrodes, both anode and cathode, in an external electrical circuit, the conductors 27, 28, 40 and 29 each are electrically connected respectively with a terminal 21 carried by the base and the envelope 13 is secured in the base in any suitable manner as by means of the insulating compound 31. Obviously, the envelope may be 45 mounted for operation and the electrodes connected in external circuits other than by the means illustrated as convenience and expediency dictate.

While the use of an exciter in conjunction 50 with any discharge device will improve its operation materially, the exciter is particularly beneficial when used with devices in which the electrodes are not artificially excited. In fact, the use of the exciter eliminates the necessity of 55 artificially exciting the electrodes, especially the cathode and makes possible the successful operation of discharge devices with so called "cold" cathode. The ability to initiate the discharge at low applied voltage is of importance since it permits the use of a simplified device-actuating system through the elimination of the cathode exciting circuit, shown in Figures 4-10, and permits the cathode to be made as a single electrode as shown in Figure 13, as distinguished from the 60 filamentary cathodes shown in Figures 2, 3, 4, 5, 7, 9, 14, and 15, and from the spaced cathode electrodes shown in Figures 6, 8, 10, 11, and 12.

In Figures 2 through 12, the exciter is applied to a discharge device embodying a permanent 70 cathode of the artificially excited type, the cathode being of filamentary character in Figures 2-5, 7 and 9, and comprising spaced electrodes in Figures 6, 8, 10-12. In Figure 13 the cathode may be "cold", that is to say, not artificially excited 75

during operation of the device. The forms shown in Figures 14 and 15 comprise devices in which the cathode and anode may alternate, or may, as is the case in Figures 2-12, maintain their status 5 as such throughout the discharging operation.

Any suitable connection or connections may be provided for exciting the cathode means and/or for impressing the alternating discharge creating potential difference upon the anodes. For instance, when the cathode is to be excited, the connections 28 and 29 may be electrically connected directly to a 110-volt alternating current supply source, while the discharge-creating potential difference may be supplied between the anode and 10 cathode means directly or through a suitable step-up transformer powered from a power source of lower voltage.

In Figures 2-6, the anode means comprises a pair of electrodes 25, which are connected to the 20 opposite ends of a secondary winding 33 of a transformer 35, the primary winding 37, of which, is connected to a suitable alternating power source. In Figures 2-4, the cathode connectors 28 and 29 are attached to the opposite ends of an auxiliary 25 secondary winding 41 of the transformer 35, while in Figure 5, the cathode connectors 28 and 29 are connected directly to a portion of the primary winding 37 of the transformer 35 while the conductors 29 also are connected through a choke 30 coil or inductive reactance 43 to the mid-point of the secondary winding 33 so that the cathode is excited by means of power delivered from the primary winding 37 either directly as in Figure 5, or through the auxiliary secondary winding 41 as 35 in Figure 4, while full wave, rectified discharge-creating potential difference is applied alternately between one or the other of the electrodes 25 and the permanent cathode means 23.

In Figures 1-6 also, the device is illustrated for 40 operation on single phase system. In Figures 7-12, three-phase operation is illustrated. In Figures 7 and 8, moreover, operation on full wave rectified power is shown, while half-wave operation is illustrated in Figures 9 and 10.

In Figures 7 and 8, the anode means comprises 45 six electrodes 25, which are connected in pairs to the opposite ends of the secondary winding 133 of a three-phase transformer 135, the primary windings 137 of which are star-connected for 50 operation on a three-phase, four-wire alternating current system, one of the cathode connections 29 being attached through the inductive reactance 143 to the mid-point of each of the secondary windings 123 of the transformer 135. The 55 cathode means may, of course, be excited from any suitable power source, but I prefer to accomplish this by connecting the connectors 28 and 29 across a portion of one phase winding of the transformer primary 137. The electrodes 25 also 60 may be arranged in any suitable or convenient location in the anode leg 22 of the channel 17 and may be disposed in adjacent alignment as shown in Figure 7. I prefer, however, to group the electrodes as snugly as possible and as near the end 65 of the anode leg of the channel and to this end, said anode leg 22 may be extended beyond the end of the cathode leg 18, as shown in Figure 8, in order to permit some of the electrodes 25 to be attached on the anode leg below the end of the 70 cathode leg. One or more of the electrodes 25 may be disposed in the lower end of the anode leg as shown in Figures 2-6, 8, and 10, while other electrodes may enter at the sides of the leg. The electrodes, which enter at the sides of the leg, also 75 enter said leg in a common plane intersecting the

axis of the envelope substantially at right angles, as shown among others in Figures 11 and 12. The arrangement of the electrodes is a matter of convenience and the most suitable arrangement will be determined by the size of the tube and the 5 number of electrodes to be mounted and depends principally upon the limitations of the glass-blowing art. It should be understood that the invention is not necessarily limited to any particular arrangement of the anode and cathode 10 means.

In Figures 9 and 10, I have shown an arrangement adapted for three-phase half-wave operation. The anode leg 22 of the channel 15 carries three anode electrodes 25, which are connected 15 to the ends of the three-phase, star-connected, secondary winding 331 of the transformer 351, the phases of the primary winding 371 of which are likewise star-connected and powered from a three-phase, four-wire alternating current system. The cathode means 23, which in Figure 9, 20 comprises the filament 24, and in Figure 10, comprises the spaced electrodes 26, may be excited from any suitable power source. To this end, the cathode connectors 28 and 29, in the illustrated 25 embodiment, are attached across a portion of one of the primary phases of the transformer. One of the conductors 29 also is connected to the common phase connection of the transformer secondary through an impedance 431 whereby a discharge occurs between each electrode 25 and the cathode means during one-half of each alternation induced in the phase of the secondary with which the electrode is connected.

In Figures 11 and 12, I have illustrated a way 30 in which the construction shown diagrammatically in Figure 10 may be employed in a practical commercial lamp. The electrodes 25 and 26 are mounted in electrode housings formed on the envelope 13 in communication with the legs of 40 the channel 17. It is desirable to connect the electrode housings to the envelope 13 in a plane intersecting the axis of the envelope substantially at right angles in order to conserve space and locate all the electrodes as near to the end 45 of the envelope as possible whereby to facilitate connections and enable the said end of the envelope, with the electrode housings extending downwardly, to be arranged snugly for reception in the support casing 15, in which the end 50 of the envelope, containing the electrode housings, is secured by means of insulating compound 31 55 powered into the cup-shaped casing 15 after the end of envelope has been assembled therein. The casing 15 also carries terminals 21, to which the electrode connectors 27, 28, and 29 are electrically connected to provide means whereby the electrodes 25 and 26 may be connected in an external circuit for powering the lamp merely 60 by inserting the casing 15 and the prongs 21 in a suitable power outlet socket having power-supplying terminals adapted to contact the terminals 21 and thus complete electrical circuits to the electrodes 24 and 25.

The commercial devices shown in Figures 1, 65 2, 3 and 11 likewise have their electrode housings 40 arranged in as neat and compact a manner as possible at one end of their envelopes 13. By keeping the electrodes as small as possible, space may be conserved by applying the electrode 70 housings 40 at the ends of the legs 18 and 22 of the channel 17, so that the electrode housing extensions do not project radially beyond the side walls of the envelope 13.

It should be understood that all of the forms 75

of discharge device herein illustrated are novel; that the exciter means X may be applied to all of the forms of discharge device illustrated herein as well as to any other common or known 5 form of discharge device; and that like or equivalent parts shown in the various embodiments are interchangeable in order to serve the purposes and attain the advantages to be accomplished by multiplying the indicated permutations and combinations. My invention is conceived to cover many inherent functional advantages not specifically mentioned herein, which will, however, be understood and appreciated by those skilled in the art.

15 It is thought that the invention and numerous of its attendant advantages will be understood from the foregoing description and it is obvious that numerous changes may be made in the form, construction, and arrangement of 20 the several parts without departing from the spirit or scope of my invention, or sacrificing any of its attendant advantages; the forms herein described being preferred embodiments for the purpose of illustrating my invention.

25 Having thus described my invention, what I claim as new and desire to secure by Letters Patent is as follows:

1. A gaseous conduction device comprising an envelope defining a sealed channel having legs 30 containing a gaseous medium adapted to be energized to sustain electrical discharge therein, said channel having portions disposed adjacently with dielectric means therebetween, spaced electrodes communicating with said adjacently disposed portions of the sealed channel to energize 35 the gaseous medium therein, and an exciter operatively associated with said adjacently disposed channel portions and comprising a conductor embracing the adjacently disposed channel por- 40 tions of said exciter and having terminals, the spaced electrodes of the discharge device being contained in envelope extensions and being received, together with the terminals of the exciter, and secured in a supporting base carrying 45 terminals electrically connected with the exciter terminals and with the electrodes to facilitate mounting the device and connecting it with external electrical power circuits.

2. A gaseous conduction device as set forth in 50 claim 1, wherein the conductor, comprising the exciter, is an elongated gaseous conduction element.

3. A gaseous conduction device comprising an envelope defining an elongated sealed channel 55 containing gaseous means adapted to be energized to sustain electrical discharge therein, said channel having end portions disposed adjacently, with dielectric means interposed between said portions, cathode means in one of said end portions and adapted to be energized for electron 60 emission, a plurality of anodes in one of said end portions, means to energize said cathode means from an external power source, and means to apply an alternating potential difference from a 65 suitable source between said anodes and to connect a neutral point of said source with the cathode means.

4. A gaseous conduction device as set forth in 70 claim 3, including exciter means operatively associated with said adjacently disposed channel portions.

5. A gaseous conduction device comprising an envelope defining an elongated sealed channel

containing gaseous means adapted to be energized to sustain electrical discharge therein, said channel having end portions disposed adjacently, with dielectric means interposed between said 5 portions, cathode means in one of said end portions and adapted to be energized for electron emission, anode means comprising spaced electrodes in another of said end portions, means to connect said spaced electrodes to an alternating current power distributing winding, and means to energize said cathode means and to connect the same with a neutral point in said power distributing winding whereby to apply a rectified potential difference between said anode and cathode means.

15 6. A gaseous conduction device as set forth in claim 5 in combination with exciter means operatively associated with said adjacently disposed channel portions.

7. A gaseous conduction device comprising a 20 tubular envelope formed to provide a sealed channel having adjacently disposed intersecting legs communicating one with the other at the point of intersection, said legs being separated by integral parts of the envelope forming a partition 25 between said legs, an anode in the extremity of each leg of said channel, and a cathode at the intersection of said legs whereby, when alternating potential is applied between said anodes, unidirectional current flow may be caused through 30 said cathode.

8. A gaseous conduction device as set forth in 35 claim 7, in combination with exciter means operatively associated with said adjacently disposed intersecting legs.

9. A gaseous conduction device comprising an envelope defining an elongated sealed channel containing gaseous means adapted to be energized to sustain electrical discharge therein, said channel having end portions disposed adjacently, with dielectric means interposed between said 40 portions, cathode means exposed in said channel, a plurality of anodes exposed in said channel, at least one of said anodes being disposed in one of said end portions, and means to apply an alternating potential difference, from a suitable power source, between said anodes and to connect a neutral point of said source with the cathode means, including reactance means connected between the cathode means and said neutral point. 45

10. A gaseous conduction device as set forth in 50 claim 9, wherein said power source comprises a distributing winding, and wherein at least two of said anodes are connected at spaced points on the winding, with the cathode means connected to the winding intermediate the anode connections thereon.

11. A gaseous conduction device as set forth in 55 claim 9, wherein the power source comprises a three-phase star-connected power distributing winding, and wherein the conduction device is provided with at least three anodes connected each to an end of the three-phase winding, with the cathode means connected to the common phase point of said winding.

12. A gaseous conduction device as set forth in 60 claim 9, wherein the anodes are connected in pairs respectively to spaced points in several windings of a poly-phase distributing system comprising the power source, the cathode means being connected to each of the several windings intermediate the anode connections thereon.

ROBERT E. BARCLAY.
